HORIZONTALLY SWINGING AUXILIARY
SEAT FOR BARBERS, DENTISTS, AND
THE LIKE

James F. Cooper, Darby, Mont.

Application May 11, 1948, Serial No. 26,417

4 Claims. (Cl. 155—81)

1

My invention relates to a seat for a barber, a dentist or like specialists, whose work requires him to stand virtually all during his working hours, and more specifically to a seat for such persons whose work is in conjunction with a patient or customer seated in a swivel chair. As is well known, such chairs are usually swiveled about, raised or lowered to suit a given situation, and the barber or dentist must move about correspondingly for the most part. Likewise, the barber or dentist must at times move relatively to the swivel chair.

With the foregoing in view, it is an object of my invention to provide an improved seat for barbers, dentists and the like.

A further object of the invention is to provide an improved seat for use with swivel chairs, a trackway mounting said seat for movement about a swivel chair relative thereto, said trackway comprising an overhead track concentrically disposed relative to the chair in vertically-spaced relation.

A further object is to provide an improved seat for use with a swivel chair which includes means for rotating the seat about the chair relatively thereto and means for coupling the seat to the chair for swivel movement therewith as a unit.

A further object is to provide improved means for suspending a seat for a swivel chair from an overhead track for the seat, which means includes means for varying the height of the seat relative to the track.

Other objects and advantages reside in the particular structure of the invention, of the elements forming the same, combination and arrangement of such elements, and will be readily understood by those skilled in the art upon reference to the attached drawing in connection with the following specification, wherein the invention is shown, described and claimed.

In the drawing:

Figure 1 is an elevational view of the swivel chair, showing the preferred form of the invention in operative association therewith;

Figure 2 is a plan view thereof with parts broken away and shown in horizontal section substantially along the line 2—2 of Figure 1;

Figure 3 is a front view of the chair with the hanger and track in section;

Figure 4 is a slightly enlarged fragmentary elevation showing a detail of the seat according to the invention;

Figure 5 is an enlarged transverse vertical sectional view showing a detail.

Referring specifically to the drawing, wherein

2

like reference characters have been used throughout the several views to designate like parts, 10 designates generally any suitable swivel chair, such as a barber's or dentist's chair, which includes a pedestal 11 swivelly and vertically adjustably mounted in any suitable base 12. The base 12 is supported on any suitable horizontal surface, such as the floor 13. A ceiling 14 is provided in vertically-spaced relation to the floor 13 above the chair 10.

As so far described, the structure is conventional and forms no part of the present invention.

As best seen in Figures 1, 2 and 3, a substantially circular track 15 comprises a pair of substantially circular inner and outer rails 16 and 17, which are suspended in vertically-spaced relation to the ceiling 14 by any suitable hangers 18. Any suitable fastening means, such as the bolts or lag screws 19, may be utilized to support the hangers 18 from the ceiling 14. The track 15 is disposed above the chair 10 in vertically-spaced concentric relation relative thereto. The inner and outer rails 16 and 17 are spaced apart slightly to provide a substantially circular space or slot 21 therebetween. As is readily apparent from Figure 2, the rails 16 and 17 have free ends 22 and 23 which are slightly spaced apart to provide means for introducing a carriage, to be described later, onto the track provided by the rails 16 and 17. Such free ends 22 and 23 are supported by slightly spaced hangers 20 from the ceiling 14. When and if it is desirable to make the track 15 completely circular, arcuate rail segments 24 and 25 are placed between the free ends 22 and 23 to span the gaps therebetween, the segments resting upon the hangers 20. These segments may be removed by lifting same from the hangers 20 and out of the gaps between the free ends 22 and 23 of the rails 16 and 17.

40 A carriage, generally indicated at 26, is supported by the track 15 and rolls on the rails 16 and 17 thereof. The carriage 26 is substantially simple in form and comprises an axle 27 having wheels 28 journaled on opposite ends thereof for rolling engagement with the rails 16 and 17 under the same. A support 29 which may comprise a depending shaft fixed to the axle 27 is provided and the lower end of such support is preferably formed to provide a substantially spherical knob 30. A casing comprising separable sections 31 and 32 partially encircles the knob 30 to provide therewith a universal joint. The sections 31 and 32 are detachably connected together in any usual and/or well known manner. 55 A stem 33 is fixed to the lower joint-providing

section 31 and depends therefrom. The lower end of the stem 33 has fixed thereto a cross-shaft or cross-arm 34. A pair of pulleys 35 are journaled on each end of the cross-shaft 34 for a purpose to be described later.

A seat, generally indicated at 36, is provided for a barber or dentist and comprises a seat-providing portion 37, a back rest 38 and a foot rest 39. A forward portion of the seat portion 37 is provided with a transverse shaft 40, the outer ends of which extend laterally outwardly of such portion 37. Pulleys 41 and 42 are journaled on such free ends of the shaft 40 to receive flexible suspension members 43 and 44. Likewise, side portions of the seat portion 37 are provided with eyes 47 to secure one end of the flexible suspension members 43 and 44 to the seat 36. Likewise, lateral end portions of the upper part of the back rest 38 are formed to provide eyes 45 through which such flexible suspension members extend upwardly. As is readily seen in Figures 1, 2 and 3, the suspension member 43 extends upwardly through the left-hand eye 45 over the innermost left-hand pulley 35 on the shaft 34, downwardly over the left-hand pulley 42 of the shaft 40, and then upwardly over the outer left-hand pulley 35 and terminates in a downwardly-directed free end. As best seen in Figures 1 and 5, a suitable brake 46 is fixed to the shaft 34 in the region of the outermost pulley 35 and has teeth on one side thereof frictionally engaging the flexible suspension member 43 when a load is imposed on the seat to lock the suspension member against movement over the several pulleys. Such brake 46 may be manually released to permit lowering of the seat 36 to a desired adjusted height. To raise the seat, however, it is only necessary to pull down on the free ends of the flexible members 43 and 44, whereby the seat is raised. Release of such free ends re-engages the brake 46 and locks the seat in an adjusted vertical position.

Referring now to Figure 4, it is seen that the front central portion of the seat portion 37 is provided with a pivoted depending socket 48 which slidably and adjustably receives the upwardly-directed stem 49 of a forwardly-extending connector arm 50. The arm 50 terminates forwardly in a downwardly-directed hook 51, the purpose of which will be described presently. The stem 49 is adjustable vertically in the socket 48 and maintained in vertically-adjusted relation by any suitable means, such as a set screw 60 or like well known locking means. As best seen in Figure 1, the seat portion of the chair 10 is provided with a circumferential series of eyes 52 which are adapted to detachably-receive the hook 51 of the connector arm 50, whereby the seat 36 may be connected to the chair 10 for swiveling action therewith as a unit. The vertical adjusted connection between the arm 50 and the seat 36 permits compensation for vertical adjustments of the chair 10 relative to the base 12 thereof. As best seen in Figures 1 and 2, the arms and back rest of the chair 10 are likewise provided with a circumferential series of eyes 53 which are adapted to receive the hook 51 in the event of the major vertical adjustment of the seat 36 relative to the chair 10 which is too great to be compensated for by the adjustment of the stem 49 in the socket 48.

In operation, it is obvious that with the connector arm 50 disconnected, the barber or dentist may be freely movable about the chair 10 relative thereto on the track 15. At the same time, when

it is desirable for the occupant of the seat 36 to move with the chair 10 as the same is swiveled in the base 12, the connector arm 50 is connected to a suitable eye 52 or 53 in accordance with the desired position, and the seat and chair thereafter moved as a unit. By providing an overhead track 15, the floor of the shop or office is not impeded by a circular track and the seat 36 is free to move over obstacles on the floor 13.

10 It should be noted that the forward portion of the seat-providing part 37 is provided with a pair of laterally-spaced and forwardly-directed end notches 54. Such portion 37 is likewise provided with an intermediate forwardly-directed notch 55. Any suitable spindle 56 extends transversely across the forward portion of the seat portion 37 and extends across the notches 54 and 55 aforesaid. The upper ends of the legs 57 of the foot rest 39 are pivoted on the spindle 56 within the end notches 54. Thus, the foot rest 39 is swingable from the full line position, Figure 4, to the broken line position where it rests atop the frame of the seat 36. Likewise, the socket 48 for the stem 49 of the arm 50 has its upper end pivoted 20 on the spindle 56 in the intermediate notch 55. Thus, the socket 48, together with the arm 50, is swingable from the full line position to the broken line position, Figure 4, where it overlies the seat-providing portion 37 of the seat and is retained 25 in the broken line position by the weight of the connector arm 50. Thus, when the foot rest and arm 50 are not in use, they may be folded to the inoperative position shown in broken lines, Figure 4.

30 35 While I have shown and described what is now thought to be a preferred embodiment of the invention, it is to be understood that the same is susceptible of other forms and expressions. Consequently, it is not my intention to limit myself to the precise structure shown and described hereinabove except as hereinafter claimed.

I claim:

1. The combination with a swivel chair, of a circular overhead track concentrically of said chair in vertically-spaced relation thereto, a wheeled carriage rotatable on said track, a support carried by said carriage and depending therefrom, suspension means carried by said support, a seat carried by said suspension means, and means for readily detachably connecting said seat to said chair for swivel movement therewith as a unit.

2. The combination with a swivel chair, of a circular overhead track concentrically of said chair in vertically-spaced relation thereto, a wheeled carriage rotatable on said track, a support carried by said carriage and depending therefrom, suspension means carried by said support, a seat carried by said suspension means, a connector arm carried by said seat and extending forwardly thereof toward said chair, said arm having an inner free end formed to provide a hook, said chair being provided with a circumferential series of eyes, and said hook being adapted to be detachably secured to a selected one of said eyes to couple said seat and chair together for swiveling movement as a unit.

3. The combination with a swivel chair, of a circular overhead track concentrically of said chair in vertically-spaced relation thereto, a wheeled carriage rotatable on said track, a support carried by said carriage and depending therefrom, a seat arranged in spaced relation with respect to said chair, a connector arm carried by said seat and extending forwardly thereof to-

ward said chair, said arm having an inner free end formed to provide a hook, said chair being provided with a circumferential series of eyes, said hook being adapted to be detachably secured to a selected one of said eyes to couple said seat and chair together for swiveling movement as a unit, and suspension means connected to said seat and carried by said support for adjusting said seat vertically relative to said track.

4. The combination with a swivel chair, of a circular overhead track concentrically of said chair in vertically-spaced relation thereto, a wheeled carriage rotatable on said track, a support carried by said carriage and depending therefrom, a seat arranged in spaced relation with re-

5

spect to said chair, suspension means arranged below said support and connected to said seat, and a universal joint connecting said suspension means to said support.
